UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

GRADUATED AIR-FEED RELIEF FOR ROCK DRILLS.

Application filed October 5, 1922. Serial No. 592,483.

One object of the invention is to enable the air feeding element to be regulated as desired by a pressure controlling device, which may be manipulated by hand and is 5 sufficiently sensitive and accurate to cause the feeding element to respond substantially in accordance with the degree of movement of the regulating device or force applied to move the device.

10 Another object of the invention is to secure a pressure controlling device by means of which the feeding element may be started and continued in operation or checked and held substantially stationary in a condition 15 of equilibrium without dropping back or may be otherwise manipulated with certainty and precision, both on starting a hole and after drilling has commenced.

The invention is shown in the accompanying 20 drawings, in which—

Figure 1 is a side elevation partly in longitudinal section of a stope drill embodying the invention,

25 Figure 2 is an enlarged detail transverse sectional view taken through the regulating valve on the line 2—2 of Figure 1 looking in the direction of the arrows,

30 Figure 3 is an enlarged detail longitudinal sectional view partly broken away through the regulating valve on the line 3—3 of Figure 2 looking in the direction of the arrows, and

Figure 4 is a side view similar to Figure 3 with the valve in a different position.

35 Referring to the drawings, which illustrate the invention applied to a stope drill, it is to be understood that only so much of the operative parts of the stope drill are shown as will serve to explain the invention 40 and its operation.

The machine comprises a cylinder A, adapted to contain a fluid actuated hammer piston, and the drill steel B extends within the front head C to receive the blows of impact of the piston. The front head C is connected to the cylinder by means of the usual side bolts D and the cylinder back head E, the head block F, and the feed cylinder head G of the feed cylinder H, are 45 connected together by the bolts J. A feed piston K having a piston rod L moves in the feed cylinder H and the piston rod is provided with a rock engaging point O. The motive fluid for operating the machine 50 is supplied at the throttle P, manipulated

by the handle Q, mounted on the back head E. The ports and passages for supplying motive fluid to the cylinder A are not indicated, as they form no part of the present invention. The passage R indicated in dotted lines in Figure 1 leads to the head block F and from thence to the air feed cylinder H for supplying pressure fluid to the feeding element. The supply of pressure fluid to the feeding element and the escape of 60 pressure fluid from said element are controlled by the hand manipulated valve S mounted in a valve chest T contained in the head block F.

The back head E of the machine is provided with the usual handle U commonly called the rotation handle, and the valve S is manipulated by means of the hand lever V pivoted at W on the head block F and provided with a lever arm X bearing on the 70 end Y of the valve S projecting from the valve chest. A spring Z normally maintains the hand lever V in retracted position, but as this lever is mounted adjacent the rotation handle U, both levers U and V are 75 grasped by the operator at the same time and by pressing upon the lever V the controlling valve S will be manipulated to a greater or less extent according to the degree of pressure applied to the lever V and in accordance with the movement of said lever.

The valve S, as shown, is hollow and contains a spring a, bearing at one end against a plug b containing an atmospheric vent c communicating with the interior of the 80 valve.

The valve chest T formed in the head block F is in this instance provided with the series of ports d forming graduated supply ports leading to the air feed cylinder H and 85 controlled by the valve S. The valve is provided with the groove e cooperating with the supply ports d.

In this instance, the valve chest is formed with the groove f cooperating with the escape ports g in the valve body S forming 90 graduated escape ports.

The valve and its ports and passages are so constructed and arranged, that the supply to the air feed cylinder H through the 105 supply ports d and thence around the groove e and thence through the port h to the air feed is never entirely cut off, so that motive fluid is continually being supplied to the air feed cylinder regardless of the position of 110

the valve. The valve is shown in normal position in Figure 3 with full supply passing to the air feed cylinder, and the escape of fluid through the port *j* is entirely cut off. 5 By pressing upon the lever handle *V*, the valve *S* is moved longitudinally in the chest against the spring *a* and as the valve is moved, the supply port *e* is continually reduced, but the amount of pressure fluid permitted to escape through the escape ports *g* is continually increased until the valve reaches the position shown in Figure 4 at the limit of its inward travel. Motive fluid is still being supplied in the minimum 10 amount to the air feed cylinder, while the maximum amount of fluid is escaping from the cylinder through the escape ports *g* and thence through the valve to the atmosphere at the port *e*. At intermediate 15 positions of the valve, fluid is being supplied to the cylinder at the same time that fluid is escaping therefrom. By means of this arrangement and because of the fact that the supply to the cylinder is never entirely cut off, although the escape or bleeder ports may be fully open, I am enabled to obtain extremely sensitive regulation and control of the air feeding element. I have found that in accordance with my construction, I am enabled to start and stop the feeding of the machine at will and hold the machine substantially stationary at any desired point without permitting the air feed cylinder to drop back on the piston *K*. 20 This is an important feature, because accidents may result if the air feed permits the machine to sink when not desired, while on the other hand I am enabled to instantly check the feeding by pressing to the required 25 extent upon the controlling handle *V* of the regulating device. My controlling device is extremely sensitive because the air feed control is graduated through a sufficient range to obtain any desired result in a positive manner.

I claim:

1. A controlling device for the air feeding element of a fluid actuated rock drill comprising a valve chest, a plurality of spaced supply ports and relief port means in said valve chest, a reciprocating valve in the valve chest to control the supply ports, said valve being hollow and provided with apertures extending through the side of the valve to communicate with the said relief port means in the valve chest, a lever mounted pivotally on the valve chest to move said valve in one direction to close the supply ports and open the relief port means gradually whereby air in the air feed element may be gradually released, and means in the valve for automatically moving the valve in the opposite direction. 50 55 60

2. A controlling device for the air feeding element of a fluid actuated rock drill comprising a valve chest, a plurality of spaced supply ports and relief port means in said valve chest, a reciprocating valve in the valve chest to control the supply ports and relief port means, said valve being hollow and provided with apertures extending through the side of the valve to communicate with the said relief port means, a spring normally tending to hold the valve in position opening the supply ports, and manually operable means to move said valve in a direction to close the supply ports and open the said relief port means gradually whereby air in the air feed element may be gradually released. 65 70 75

3. A controlling device for the air feeding element of a fluid actuated rock drill comprising a valve chest provided with a plurality of spaced supply ports and relief port means, a reciprocating valve in the chest to control the supply ports and the said relief port means and having an end projecting from the valve chest, said valve being hollow and provided with apertures extending through the side of the valve to communicate with the said relief port means, a lever mounted pivotally on the valve chest to move said valve in one direction to close the supply ports and open the relief port means gradually whereby air in the air feed element may be gradually released, and a spring in said valve for automatically moving the valve in the opposite direction for closing the relief port means and opening the supply ports. 80 85 90 95

4. A controlling device for the air feeding element of a fluid actuated rock drill comprising a valve chest provided with a plurality of spaced supply ports and relief port means, a reciprocating valve in the chest to control the supply ports and the said relief port means and having an end projecting from the valve chest, said valve being hollow and provided with apertures extending through the side of the valve to communicate with the said relief port means in the valve chest, a lever mounted pivotally on the valve chest to move said valve in one direction to close the supply ports and open the relief porting gradually whereby air in the air feed element may be gradually released, a spring in said valve for automatically moving the valve in the opposite direction for closing the relief porting and opening the supply ports, and a spring in the valve chest for holding the lever in a normally retracted position. 100 105 110 115 120

In testimony whereof I have signed this specification.

FRED M. SLATER.
